No. 783,055.

PATENTED FEB. 21, 1905.

P. LE SUEUR.

LUBRICATING DEVICE FOR VEHICLE AXLES.

APPLICATION FILED OCT. 28, 1903.

UNITED STATES PATENT OFFICE.

PHILIP LE SUEUR, OF CALABASAS, CALIFORNIA.

LUBRICATING DEVICE FOR VEHICLE-AXLES.

SPECIFICATION forming part of Letters Patent No. 783,055, dated February 21, 1905.

Application filed October 28, 1903. Serial No. 178,833.

To all whom it may concern:

Be it known that I, PHILIP LE SUEUR, a citizen of the United States, residing at Calabasas, in the county of Los Angeles and State of California, have invented a new and useful Lubricating Device for Vehicle-Axles, of which the following is a specification.

This invention relates to a new and useful construction of a vehicle-axle; and the main object of the invention is to provide means whereby the lubricating composition may be supplied to the axle without removing the wheel from the axle and without removing the retaining-bolt or outside hollow nut or other part, the construction being so designed that while accomplishing the foregoing the wheel may be as easily removed as when the vehicle-axle is ordinarily constructed.

Another object of my invention is to provide means whereby the too rapid escape of oil from the outer oil-chamber to the inner oil-chamber is regulated by the size of the orifice in end of semiblind axle-box.

Another object is to provide a device of the character described which will permit of using either thin or thick oils or hard grease, as desired.

The present invention is of great value for wagons used in teaming in very hot countries, especially on mountain roads. The extreme heat in such places and violent chucking on the hilly roads causes oil to run like water out of ordinary journal-boxes.

My invention enables hard grease to be employed as readily as oil, and the grease may be applied in a compact mass of considerable quantity, so that replenishment of the supply is not required with near the frequency necessary when using oil in hot districts.

Another object is to provide a construction simple in design which automatically closes the orifice for the introduction of oil, which is durable in use, which will not get out of order, and which may be economically manufactured.

Another object of my invention is to provide means whereby the full diameter of the axle may be flooded with oil.

Another object is to provide a construction which while possessing the foregoing advan-

tages is very economical in use for the following reasons: first, that the vehicle can be effectively lubricated in one quarter the time required to lubricate any other improved vehicle on the market; second, that less oil is required for a given length of time to maintain the necessary lubrication than is required in axles of the ordinary construction, there being provision made for retaining oil in a quantity, so that it is fed to the axle continuously and is prevented from oozing away, as is the case of axles of the ordinary construction.

Another object is to provide a construction which effectually prevents dust or grit from entering the axle and injuring the working parts, likewise preventing dirt from closing up the lubricating-slots.

The accompanying drawings illustrate the invention, and, referring to the same, Figure I is a longitudinal section through the device. Fig. II is a longitudinal section showing the preferred construction. Fig. III is a perspective view showing the preferred form of outer end of the axle-box. Fig. IV is a perspective view showing another form of outer end of the axle-box. Fig. V is a view of the outer face of the retaining devices, showing them in one position shutting off the outward escape of oil. Fig. VI is a similar view showing the parts in another position adapted for the admission of a supply of oil. Fig. VII is a detail view of the outer face of the hollow nut. Fig. VIII is a plan view of the bolt-head used in the form shown in Fig. II. Fig. IX is a perspective, with portions broken away, of the screw-collar used in Fig. I.

1 designates the axle, the outer end of which is drilled and tapped, as shown.

2 is a semiblind axle-box, preferably tapered, as shown, which fits snugly within the hub 3 and is prevented from turning therein by means of radial projections 4.

The outer end of the axle-box 2 is provided with a lip 5, (see Figs. I and IV,) and the end of the axle 1 terminates short of the end of the axle-box 2, thereby forming an oil-reservoir, into which oil or grease may be introduced.

7 is a retaining-bolt which screws into the

end of the axle 1. Said retaining-bolt is provided with an elongated smooth shank and is provided with a flange 8. The flange 8 is provided with a series of oil-holes 9.

10 is a screw-collar, which is screwed onto the outer end of the axle-box 2 and is cupped on both faces, forming a central web 11. The web 11 is provided with an oil-hole 12, and 13 is a washer, of leather or other packing material, which is nested within the outer cupped portion of the nut 10 and lies closely against the web 11. The leather plate 13 is rendered non-turnable by pins 14, and in addition the walls of the screw-collar 10 are undercut 15 slightly, as at 15, to receive the washer 13, which is sprung into place when assembling the parts of the nut, and hence is easily replaced. The leather plate 13 is provided with an oil-hole 16, which exactly registers with 20 the oil-hole 12 in the web 11, and when the screw-collar 10 is screwed firmly into position over the end of the axle-box 2 the oil-box 12 is covered by the lip 5, and when the retaining-bolt 7 is screwed to position one of its series of oil-holes 9 in its flange 8 may or may 25 not be in register with the oil-holes 16 and 12. When it is desired to lubricate the axle, the screw-collar 10 is turned until the oil-hole is at the highest point of the hub. The bolt is 30 also turned to bring one of the oil-holes 9 into register with the hole 16 in the screw-collar, when the spout of an oil-can may readily be introduced and the axle flooded with oil to its full diameter. After sufficient oil has been 35 introduced the screw-collar 10 is tightened, which causes its oil-hole to be covered by the lip 5, thus preventing the escape of oil, and the bolt 7 is also tightened.

40 The leather plate 13 closely fits the shank of the retaining-bolt 7, so that the escape of oil from the bearing is impossible, and the ingress of dirt or grit into the bearing is also prevented, as the lip 5 covers the oil-hole 12.

45 A bearing-plate 16 is preferably mounted on the end of the hub to form a bearing-surface against the inner edge of the screw-collar 10.

50 Introduced between the end of the retaining-bolt 7 and the bottom of the hole in the end of the axle 1 is a bolt-stop 17, having a concave head which fits the convex end of the retaining-bolt 7 and forms a positive mechanical stop to position the bolt 7 when screwed home. A coil-spring 18 encircles the shank of bolt-stop 17 and presses against the head of 55 the bolt-stop, thus forcing the screw-threads of the retaining-bolt tightly into engagement with the threads in the axle, thus forming a novel bolt-lock and holding the retaining-bolt from turning accidentally or getting loose 60 from the jar of the wagon.

19 is a washer which bears against the inner end of the axle-box 2, being resiliently pressed against the box 2 by a spring-washer 20. The two washers 19 and 20 are mounted

in an adjustable shoulder 21. The washers 65 19 and 20 and adjustable shoulder 21 are covered in another application of mine, filed October 28, 1903, Serial No. 178,834.

Figs. II and III show the preferred form of construction in which the end of the axle-box 2 has cast thereon a retaining-wall 22, which is centrally drilled and at one side, preferably its lower side, provided with an oil passage-way 23. Projecting from the retaining-wall 22 is a standard 24, having a shield 25. 70 A hollow nut 26 is screwed onto the end of the axle-box 2 and is provided with an oil-hole 27, which when the nut 26 is screwed into place is covered by the shield 25, thus positively retaining the lubricant in the bearing 80 when the oil-hole is brought to any point by the turning of the wheel. The nut houses the head of the bolt 7. The bolt 7 is screwed up, so that the face of the bolt engages the end of the axle-box. The position of the oil-hole 27 85 constantly changes as the wheel turns, and when the vehicle is stopped for oiling the oil-hole 27 may be at the bottom, or it may be at the top of the hub or at an intermediate position. Obviously the oil-hole 27 should be preferably at or near its highest point when oil is 90 to be supplied, so that the hollow nut will retain the oil as it is introduced. Therefore in oiling if the oil-hole is not sufficiently near the top the nut should be turned to bring it to that 95 position, which brings its oil-hole 27 away from the shield 25, thereby permitting the spout of an oil-can to be inserted through the oil-hole. After sufficient oil has been introduced the nut 26 should again be tightened, so that 100 the shield 25 closes the oil-hole 27.

A valuable feature of the present invention is that when the vehicle is standing still oil may positively be prevented from running out by turning each wheel to bring the slot 23 to 105 its highest point. The proper point to which to turn the wheel may readily be determined by the oil-hole 27, which when the nut 26 is properly screwed home is diametrically opposite the slot 23 and being exposed is in plain 110 view, so that when the wheel is turned to bring the oil-hole 27 to its lowest point the slot 23 will be at its highest point and oil cannot flow through the slot and out of the inner oil-chamber. Hence the oil is retained indefinitely in the hollow nut. The interior of the nut 26 affords additional space to retain the lubricant in connection with the oil-chamber 6, so that in the form shown in Fig. 2 a 115 greater quantity of oil may be supplied at a given time than can be supplied to the form shown in Fig. 1. The size of the slot 23 should be proportioned according to the character of oil used to regulate the flow of the oil. A large heavy vehicle using thick oil 120 would require a relatively larger slot than would a small light vehicle which used a thin oil. For the thick oils the slot should be rela- 125

tively large, and for the thin oils it should be smaller.

The present invention is designed specially for use in the semitropical and semi-arid

5 Western States, where peculiar climate conditions exist. At midday in these regions the heat is so intense that oil runs off an axle like water, while at night and early morning it is so cold that grease gets very hard. Hence in 10 using my invention the inner lubricant-chamber in the axle-box is loaded with hard grease in the early morning. Then the hollow nut is screwed on and sufficient oil is introduced to bring it above the level of the retaining-bolt, 15 the bolt-hole being designedly large to allow the free passage of oil. The traction and chuck of the wheel keeps the hard grease in the inner chamber away from the smooth shank of the bolt, enabling the oil from the 20 hollow nut to have free access to the axle. Then when the great heat of the day sets in the melting grease keeps the axle lubricated and later opens the slot in the end of the blind axle-box, allowing free ingress of oil from 25 the hollow nut. Another important feature is that there are no minutely-small or intricate passages for the lubricant which would clog with grease or thick oil or thin oil which had thickened by use, and the invention is 30 therefore of especial value for heavy vehicles using grease or thick oil. The thinness of the retaining-wall in which the slot 23 is located does not afford sufficient lodgment for the accumulation of a deposit or permit gumming of the oil in the passage. The oil is fed 35 slowly yet continuously to the axle, and the too free escape of oil at the extreme inner end of the axle-box is guarded against.

In order to lock the hollow nut 26 from 40 turning by the jar, the periphery of its flange may have shallow notches 28, either one of which is engaged by a spring-finger 29, mounted in the hub and projecting therefrom. The hole in the hub in which the spring-finger 45 lies is enlarged or tapered near the outer face of the hub to permit of the spring-finger 29 freely springing to yieldingly lock the hollow nut 26. The outer end of the spring-finger 29 is preferably bent to enable the spring-finger 50 to be readily grasped by the hand to release the hollow nut when the latter is to be turned into or out of place.

The solid retaining-bolt 7 obviously performs the double function of closing the central aperture in the retaining-wall 22 and of holding the axle-box and attached parts in place on the axle. Thus when the retaining-bolt is removed the hole gives ample space 55 for the introduction of hard grease. The central aperture is designedly larger than the retaining-bolt to allow of the free ingress of oil from the auxiliary lubricating device—*i. e.*, the hollow nut—and being provided with means for the introduction of the heaviest oil

far above the level of the retaining-bolt the 65 escape of lubricant can be effected only by its traversing the axle-box, hence lubricating the axle.

While I have shown and described the preferred embodiment of my invention, it should 70 be understood that various changes and modifications may be made therein without departing from the scope of the claims.

What I claim is—

1. In combination, an axle, an axle - box 75 thereon, the end wall of the axle-box having a central hole for the introduction of lubricant, said axle terminating short of the end of the axle-box, thereby forming a lubricant-chamber at the end of the axle, and a solid 80 bolt detachably engaging the end of the axle, the shank of the bolt traversing the lubricant-chamber and passing through the hole in the end of the axle-box, the head of the bolt being outside the axle-box, the bolt being removable to open the hole and allow hard 85 grease to be put into the chamber, the bolt when in place preventing egress of the lubricant and also holding the axle-box on the axle.

2. In combination, an axle, an axle - box 90 thereon, the end wall of the axle-box having a central hole for the introduction of lubricant, said axle terminating short of the end of the axle-box, thereby forming a lubricant-chamber at the end of the axle, and a solid 95 bolt detachably engaging the end of the axle, the shank of the bolt traversing the lubricant-chamber and passing through the hole in the end of the axle-box, the head of the bolt being outside the axle-box, the bolt being removable to open the hole and allow hard grease 100 to be put into the chamber, the bolt when in place preventing egress of the lubricant and also holding the axle-box on the axle, the end wall of the axle-box also having another 105 smaller orifice for the passage of thinner lubricants, and means external of the axle-box and detachably fastened thereto for holding a supply of lubricant which may automatically feed into the inner chamber through the small 110 orifice.

3. In combination, an axle, an axle - box 115 thereon, a hub on the axle-box, the outer end of the axle-box having a retaining-wall, there being a space between the retaining-wall and the end of the axle forming a lubricant-chamber, said retaining-wall having a passage for lubricant, and a retaining-bolt passing through the retaining-wall into the axle, a hollow nut 120 screwed to the axle-box, said hollow nut having an oil-hole.

4. In combination, an axle, an axle - box 125 thereon, a hub on the axle-box, the outer end of the axle-box having a retaining-wall, there being a space between the retaining-wall and the end of the axle forming a lubricant-chamber, said retaining-wall having a passage for lubricant, and a retaining-bolt passing through

the retaining-wall into the axle, a hollow nut screwed to the axle-box, said hollow nut having an oil-hole, and means for closing said oil-hole.

5. In combination, an axle, an axle-box thereon, a hub on the axle-box, the outer end of the axle-box having a retaining-wall, there being a space between the retaining-wall and the end of the axle, forming a lubricant-chamber, said retaining-wall having a passage for lubricant, and a retaining-bolt passing through the retaining-wall into the axle, a hollow nut screwed to the axle-box, said hollow nut having an oil-hole, a standard projecting from the axle-box, there being a shield on the standard for covering the oil-hole in the hollow nut.

6. In combination, an axle, an axle-box thereon, a hub on the axle-box, the outer end of the axle-box having a retaining-wall, there being a space between the retaining-wall and the end of the axle, forming a lubricant-chamber, said retaining-wall having a passage for lubricant, and a retaining-bolt passing through the retaining-wall into the axle, and means for 25 yieldingly locking said hollow nut.

7. In combination, an axle, an axle-box thereon, a hub on the axle-box, the outer end of the axle-box having a retaining-wall, there being a space between the retaining-wall and the end of the axle, forming a lubricant-chamber, said retaining-wall having a passage for lubricant, and a retaining-bolt passing through the retaining-wall into the axle, said retaining-bolt having a smooth shank traversing the lubricant-chamber.

8. In combination, an axle, an axle-box thereon, a hub on the axle-box, the outer end of the axle-box having a retaining-wall, there being a space between the retaining-wall and the end of the axle, forming a lubricant-chamber, said retaining-wall having a passage for a lubricant, a hollow nut screwed to the axle-box, said hollow nut having an oil-hole, and a bearing-plate interposed between the hollow nut and the face of the hub.

9. In combination, an axle, a semiblind axle-box thereon forming an oil-chamber between the end of the axle and the end of the semiblind axle-box, a hollow nut screwed to the end of the semiblind axle-box, the end of the semiblind axle-box having passages for lubricant, and the hollow nut having an oil-hole.

10. In combination, an axle, a semiblind axle-box thereon forming an oil-chamber between the end of the axle and the end of the

semiblind axle-box, a hollow nut screwed to the end of the semiblind axle-box, the end of the semiblind axle-box having passages for lubricant, and the hollow nut having an oil-hole, said oil-hole being near the periphery of 60 said hollow nut.

11. In combination, an axle, a semiblind axle-box thereon forming an oil-chamber between the end of the axle and the end of the semiblind axle-box, a hollow nut screwed on 65 the end of the semiblind axle-box, the end of the semiblind axle-box having passages for lubricant, the hollow nut having an oil-hole, a solid retaining-bolt passing through the end of the semiblind axle-box with its shank traversing the lubricant-chamber, the shank of the bolt being smooth.

12. In combination, an axle, an axle-box thereon, the outer end of the axle-box having a retaining-wall, there being a space between 75 the axle end and retaining-wall, said retaining-wall having passages for lubricant, a hollow nut having an oil-hole screwed to said axle-box and designedly supplied with means for a circular motion from its inner surface for 80 the purpose set forth.

13. In combination, an axle, a semiblind axle-box thereon, there being a lubricant-chamber between the axle end and extreme end of the semiblind axle-box, the semiblind axle-box having in its end passages for lubricant, a hollow nut screwed to said axle-box and having an oil-hole near its periphery, said hollow nut being designedly supplied with means for a circular movement substantially as set forth and for the purpose specified.

14. In combination, an axle, the outer end of which is recessed axially and internally screw-threaded, an axle-box on the axle, the outer 95 end of which is partly closed, a hub on the box provided with a bearing-plate, a bolt through the plate and the end of the box and into the recess in the end of the axle, and means in the bore to lock the bolt against accidental removal.

In testimony whereof I have hereunto signed my name, in the presence of two subscribing witnesses, at Los Angeles, in the county of Los Angeles and State of California, this 21st 105 day of October, 1903.

PHILIP LE SUEUR.
